CLOTHESLINE STRUCTURE

Edmund A. Bumbera, Turtle Creek, and Clarence S. Herr, Jr., Penn Township, Allegheny County, Pa.; said Herr, Jr., assignor to said Bumbera

Application October 9, 1946, Serial No. 702,160

1 Claim. (Cl. 211—119.01)

1 Our invention consists in a new and improved clothes line structure.

The principal object in view is the provision of means for hanging out for drying a large "wash" in a relatively contracted area.

In many instances, such as in thickly populated localities and in building developments where the houses are built closely together or in rows with narrow back yards of a limited length, the common method of stringing a clothes line provides too limited a capacity, and thus the wash must be hung out in successive sections, requiring more time and increased labor even in the case of a small family.

To solve the problem of drying a large wash in one operation and in a contracted area, we have invented the new and improved clothes line structure, hereinafter described, and which comprises two substantially parallel supporting members, preferably chains, erected at the proper elevation, and of a length and spaced apart the distance permitted by the available yard area. Stretched between said supports in a zigzag disposal is a clothes line detachably connected to the two supporting members at staggered points and at its ends. Means are provided for connecting the clothes line to the supporting members in such a manner that the line may be quickly installed or removed and slipping of the clothes line between the flights is prevented.

To attach the clothes line to the longitudinal supporting members at the angles of the clothes line and at its ends, we provide a new and improved type of hook members which are detachably anchored to the opposed supporting members in staggered relation and with which the clothes line is engaged in such manner as to be conveniently and quickly mounted and dismounted from position and which will prevent longitudinal slipping of the clothes line.

Other points of novelty will appear from the following description.

In the accompanying drawings, which illustrate the principles of our invention,

Fig. 1 is a view in plan illustrating the clothes line structure assembled ready for hanging out the wash;

Fig. 2 is an enlarged view in perspective showing one of the hook members used to attach the clothes line to the longitudinal supporting members;

Fig. 3 is a broken elevation showing the attachment of an end of one of the longitudinal members to a fixed support, such as a post;

Fig. 4 is a detail view showing the provision of

2 means for maintaining the longitudinal members in proper tautness.

Referring to the drawings, 10 represents the two substantially parallel longitudinal supporting members which are preferably chains of the open link type, such, for instance, as the chain commonly termed a "porch swing" chain, the interconnected links of the same being indicated at 11 in Figs. 2, 3 and 4. At their extremities these 10 chains are attached to fixed supports, such as a building wall indicated at 12 or posts indicated at 13.

14 indicates a hook attached to the wall or post, as by having a threaded shank screwed into the 15 post 13, as illustrated in Fig. 3, the end link 11 of the chain 10 being looped over the hook. To enable the chains 10 to be made sufficiently taut to prevent material sagging we provide in each chain a turnbuckle 15.

20 The chains preferably are as nearly parallel and spaced as far apart as the available yard area permits.

16 indicates the clothes line, which preferably is the usual type, and is disposed between the 25 chains 10 in a zigzag manner and supported at its angles and ends by the latter.

For attaching the clothes line 16 at its angles and ends to the chains 10 we provide the hook members 17 which are formed of lengths of metal rod or wire stock. The extremities of the said 30 lengths are bent to form the hook portions 18 which face rearwardly and diverge as shown in Fig. 2. At the base of said hook portions 18 the portions 19 are bent to extend rearwardly forming with the base of the portions 18 the narrow 35 loop portions 20. At their outer ends the portions 19 converge into close parallel relation and the central portion of the length of stock is bent upwardly, then rearwardly, then upwardly and finally forwardly to form the snug central hook portion 21 which is positioned in advance of the hook portions 18.

When in use the loops 20 extend through and engage adjacent links 11 of the chain 10, thus 45 removably mounting the hook members 17 on the chains. The hook members are equally spaced apart on each chain and the hook members on one chain are disposed equally in staggered relation to those on the other chain, as 50 illustrated in Fig. 1. It is evident the hook members 17, owing to the engagement between the loops 20 and the chain links 11, cannot shift longitudinally of the chains but will maintain their proper relative positions.

55 The clothes line 16 engages from the rear the

end hook portions 18 and intermediate of such points of engagement the rope is looped around the center hook portion 21. When the clothes line is held taut and engaged in such manner that one of the hook members 17 either at an intermediate portion of the line or adjacent either extremity of the line the latter cannot shift relative to the hook member but each flight of the line between hooks is individually anchored at its ends, and therefore a heavy load of wet clothes hung on one flight will not draw line from adjacent flights and thus permit its load to sag dangerously.

The angle between adjacent flights of the clothes line as erected may be varied in accordance with the available yard area, the angles however being sufficient to provide access on the part of the operator to the clothes on adjacent flights and to prevent articles on adjacent flights from intertwining.

The new and improved clothes line structure hereinbefore described is of great advantage under modern conditions of limited yard area, enabling a large wash to be successfully dried in one operation of hanging the same in a contracted area. It may also be employed within a building compartment in which under the usual set-up but a very limited wash could be suspended at one time.

It is evident that our improved means for attaching the line at its ends and at its angles to the longitudinal supporting members prevents lengthwise slipping of the line due to ununiform distribution of the load between adjacent flights; a very important consideration as otherwise the heavily loaded flights of the line would sag and frequently the clothes on the heavily loaded flights would be brought into contact with the ground.

We claim:

In a clothes line assembly, the combination of a pair of chains arranged to be stretched in spaced relation between fixed supports, a plurality of spaced apart fastening members provided with hooked portions detachably engaging the links of said chains, the fastening members of one chain being positioned in staggered relation with the fastening members of the other chain, and a flexible clothes line stretched between the chains in a zigzag pattern with its ends and its intermediate angles secured to the fastening members and held thereby against longitudinal slipping of the clothes line.
